UNITED STATES PATENT OFFICE.

ARTHUR A. PANNIER, OF SALT LAKE CITY, UTAH.

COMBINATION-PLIERS.

1,364,137.

Specification of Letters Patent.

Patented Jan. 4, 1921.

Application filed October 8, 1919. Serial No. 329,846.

To all whom it may concern:

Be it known that I, ARTHUR A. PANNIER, a citizen of the United States, residing at Salt Lake City, in the county of Salt Lake 5 and State of Utah, have invented new and useful Combination-Pliers, of which the following is a specification.

This invention relates to pliers, and particularly to a combination tool which will 10 punch a hole in an animal's ear and will secure an ear tag passed through said hole.

The chief object of the invention is to provide a single tool which will do the work of two without any unnecessary complication 15 of its parts. Another object is to provide an instrument for securing ear tags which cannot pinch the ear. A further object is to provide a tool which will punch clean cut holes of the desired shape and size and will 20 then clench the tag in place without necessitating removal of the tool. It is also an aim of the invention to produce an ear punch which will not become dulled readily and will therefore have long life.

25 The above and other objects are attained by the embodiment of the invention illustrated in the accompanying drawing, which forms a part of this specification, and described in detail below. It will be understood 30 that the present disclosure is illustrative in character, and that many changes may be made in the construction of the device without departing from the spirit and scope of the invention as set forth in the 35 appended claims.

In the drawing:

Figure 1 is an elevation of the pliers, showing the jaws forced together and the clenching element in working position;

40 Fig. 2 is a fragmentary elevation of the pliers showing the jaws open and the punching element in working position;

Fig. 3 is a top plan view of the portion shown in Fig. 2;

45 Fig. 4 is a sectional view taken on the line 4—4 of Fig. 2;

Fig. 5 is a view of the jaw end of the pliers; and

50 Fig. 6 is a section on the line 6—6 of Fig. 4 showing the jaws closed.

The numeral 10 designates one of the lever arms of the pliers and 11 denotes the other arm. A flat spring 12 of ordinary construction is secured to one arm and bears against 55 the other to normally maintain the pliers open as shown in Fig. 2. The arms are

pivoted by an element 13, and jaws 14 and 15 united to arms 10 and 11 respectively extend beyond the fulcrum 13. The lower jaw 14 has a plate 16 secured to it of brass or 60 other soft metal which covers the outer portion of the jaw.

The upper jaw 15 has a plate 17 secured to it by a pivotal screw 18 in such a way that the plate can swing in its own plane about 65 18 as an axis. At one end the plate 17 carries a downwardly projecting upsetting block or anvil 19 while at its opposite end it carries a hollow punch 20. Thus when the plate is swung on its axis, first the one then 70 the other of the two elements just described is placed in working position. The block has a flat working face and is considerably shorter than punch 20, so that the latter encounters the lower jaw well in advance of 75 the block (see Figs. 1 and 2).

The hollow punch is of a peculiar shape, being like a flattened ellipse or rounded oblong at its cutting end and having a beveled edge 21, while it is round at its other 80 end, and is secured to the plate 17 preferably by screw threads 22, a suitable bore being provided in the plate which bore is a continuation of bore 23 in the jaw 15. It is clear that the punch tapers from its upper 85 round attaching end to its lower cutting end, is hollow throughout, and communicates with the bore 23. Thus material cut by the punch is forced up through the latter and out through the bore 23. 90

The upper side of jaw 15 carries a spring retainer 24 secured at one end only by a screw, the other end overlapping the jaw and being left free for slight movement. The resilient retainer or latch 24 has a large 95 hole 26 over the bore 23 so as to allow cuttings to pass freely out from the latter. Downwardly extending arms 27 are formed integrally with the retainer. These arms lie close beside the jaw edges and overlap the 100 edges of the plate 17 thus preventing swinging of the latter except when the latching arms 27 are lifted clear of the plate. This is easily done by pulling up the outer end of the retainer 24 with the thumb. 105

The manner in which the invention is used is simple. The animal's ear is put between the jaws with the parts disposed as Fig. 2 shows, and the pliers are squeezed shut. The sharp edge of the punch cuts a hole 110 in the ear, the cartilage passing up through the punch and ultimately out through the

bore. The ear tag is run through the hole and the clenching block 19 swung about into working position and forced down, whereupon the tag is locked securely upon the 5 ear.

The advantages of my invention are manifold. Besides being less expensive and handier to have one tool take the place of two, the punch does not become dulled 10 quickly because it strikes soft metal at the end of its stroke. The punch can be removed readily, sharpened and replaced. The block is at the extreme end of the swingable plate with the result that it overhangs 15 the opposite jaw to some extent, which is an advantage when clenching. The plate is so mounted as to give a maximum reach for cutting the hole and more than enough room when reversed to permit clamping of the 20 tag without the cutting element uselessly mutilating the ear. The ears cannot be pinched when the tags are applied because the clenching element is brought to a stop with a considerable space between it and the 25 jaw. In other words, the punch acts as a stop in the manner shown in Fig. 1.

What is claimed is:—

1. In combination pliers, a pair of jaws, a plate pivoted to one of said jaws, a punch 30 provided at one end of the plate, a clenching element at the other end of the plate, and a second plate fixed flat upon the other jaw, said punch encountering said second plate when swung into working position 35 and encountering the opposite jaw when the clenching element is in working position, upon the closing of the jaws.
2. In combination pliers, a pair of jaws, a plate pivoted to one of said jaws, a punch 40 and clenching element each secured to the plate at opposite ends thereof, said punch and clenching element being presented alternately at the outer end of the pliers when the plate is swung on its pivot, the relative 45 positions of the punch and clenching element being such that when the punch is in working position it will be wholly comprehended between the two jaws, while when the clenching element is in working position 50 it will lie partly between said jaws and partly beyond the outer edge of that jaw which holds the plate.
3. In combination pliers, a pair of jaws, a plate pivoted to one of said jaws, a punch 55 provided at one end of the plate, and a clenching element at the other end of the plate, said punch having a greater length than the clenching element whereby it serves 60 as a stop to limit the closing movement of the jaws.
4. In combination pliers, a pair of jaws, a plate pivoted between its ends to one of said jaws, a punch and a clenching element secured to the plate at opposite ends thereof, 65 said punch and clenching element being pre-

sented alternately at the outer end of the pliers when the plate is swung on its pivot, said punch having a greater length than the clenching element so as to meet the lower jaw, whatever the position of the punch, 70 with a space between the clenching element and said jaw.

5. In combination pliers, a pair of jaws, a plate pivoted to one of said jaws, a clenching element and a punch secured to said 75 plate, said clenching element lying in part beyond the outer edge of the jaw upon which it is mounted when the plate is swung to present the clenching element in working position.

6. In combination pliers, a pair of jaws, a plate pivoted to one of said jaws, a clenching element and a punch secured to said plate, said punch being hollow and having a uniform taper from a large circular end 85 screwed into said plate to a small end having a beveled cutting edge, said cutting edge having the form of a flattened ellipse, whereby it cuts holes in an animal's ear of a corresponding shape. 90

7. In combination pliers, a pair of jaws, a plate pivoted to one of said jaws, a clenching element and a punch secured to said plate, said punch being hollow and tapered with its large end screwed into said plate, 95 and its small end having a beveled elongated cutting edge, said clenching element consisting of a block having a flat working face, said punch having a greater length than the clenching element so as to meet the lower 100 jaw, whatever the position of the punch, with a space between the clenching element and said jaw.

8. In combination pliers, a pair of jaws, a plate pivoted to one of said jaws, a punch 105 provided at one end of the plate, and a clenching element at the other end of the plate, and latching means for the plate, said means comprising a resilient member secured at one end to the jaw and overlapping 110 the outer end thereof and having arms extending downwardly to engage with the edges of the plate.

9. In combination pliers, a pair of jaws, a plate swingably mounted on one of said 115 jaws, a clenching element and a hollow punch fixed to said plate, a bore in the plate-holding jaw forming an outlet for the cuttings passing up from the hollow punch, and latching means for the plate secured to 120 said jaw, said means being provided with a passageway over the bore for said cuttings.

10. In combination pliers, a pair of jaws, a plate pivoted to one of said jaws, a punch provided at one end of the plate, a clenching element at the other end of the plate, the relative positions of the punch and clenching element being such that when the punch is in working position it will be 125 wholly comprehended between the two jaws, 130

- while when the clenching element is in working position, it will lie partly between said jaws and partly beyond the outer edge of that jaw which holds the plate, and a second 5 plate fixed flat upon the second jaw, the said punch encountering the said second plate when swung into working position, and encountering the opposite jaw when the clenching element is in working position.
- 10 11. In combination pliers, a pair of jaws, a plate pivoted to one of said jaws, a punch provided at one end of the plate, a clenching element at the other end of the plate, the relative positions of the punch and clenching element being such that when the punch is in working position, it will be wholly comprehended between the two jaws, while 15 when the clenching element is in working position, it will lie partly between said jaws,
- and partly beyond the outer edge of that 20 jaw which holds the plate, a second plate fixed flat upon the second jaw, the said punch encountering the said second plate when swung into working position and encountering the opposite jaw when the clenching element is in working position, a latching means for the plate, said latching means 25 comprehending a resilient member secured at one end of the jaw which holds the plate and overlapping the outer end thereof, and 30 having arms extending downwardly to engage with the edge of the plate.

In testimony that I claim the foregoing as my own, I have hereto affixed my signature.

ARTHUR A. PANNIER.
